SUCTION CLEANER

Harold H. Boyer, Canton, Ohio, assignor to The
Hoover Company, North Canton, Ohio, a cor-
poration of Ohio

Application May 16, 1936, Serial No. 80,066

7 Claims. (Cl. 285—71)

This invention relates to suction cleaners, and more particularly to suction cleaners of the type which are portable and are adapted to be moved about, over the floor covering which is to be cleaned, by means of a rigid handle, pivoted to the body of the cleaner and extending upwardly and rearwardly therefrom. One of the important elements of a suction cleaner is a filtering dust collector, or dust bag, by which the dust entrained in the stream of air which is drawn through the nozzle of the suction cleaner can be filtered from the air, such dust collector being usually in the form of a bag of cloth or paper, or other suitable dust-filtering medium, and usually provided with a narrowed mouth which is detachably connected to the outlet from the body of the cleaner, and usually loosely supported at its upper end from the handle of the cleaner. In some suction cleaner constructions the bag is located between the dust inlet and the fan, the air being passed through the bag before reaching the fan, so as to remove the dust therefrom. The present invention relates particularly to means for detachably connecting the dust bag to the discharge outlet, whether the air is blown through such outlet or sucked therethrough.

One of the objects of the present invention is to provide suitable means for detachably connecting a suction cleaner bag which may be readily operated to attach or detach the bag and which is particularly adapted for the attachment of bags of simple structure, which can be economically manufactured. A further object of the invention is to provide attaching means for this purpose which can be economically manufactured, which will be simple of operation, and which will be effective in preventing leakage. Further objects of the invention are to provide attaching means of this kind by which the bag will be held positively in its attached position, which can be substituted for other attaching means, heretofore used on cleaners already manufactured and in use, and attaching means in which the danger of operation in an improper manner is reduced to a minimum.

Still further objects of the invention and features of novelty will be apparent from the following specification, when read with reference to the accompanying drawings, in which embodiments of the invention are illustrated, and in which:

Fig. 1 is a fragmentary view in side elevation of a suction cleaner embodying the invention; 50 Figs. 2 and 3 are enlarged views in vertical

section showing the bag in its position preliminary to attachment, and in its attached position, respectively;

Fig. 4 is an enlarged view in front elevation of the structure shown in Fig. 2; 5

Fig. 5 is an enlarged view in cross section, taken on the line 5—5 of Fig. 2;

Fig. 6 is an enlarged fragmentary plan view of the structure shown in Fig. 2;

Fig. 7 is an enlarged fragmentary view, in perspective, of the mouth of the bag shown in the other figures, certain of the parts being broken away to disclose the structure more clearly;

Figs. 8 and 9 are enlarged views in vertical section similar to Figs. 2 and 3 but showing a modified structure of bag securing fingers.

In the drawings a suction cleaner body, comprising a wide, forwardly-positioned nozzle 11, a fan chamber portion 12, having an outlet 13 terminating in a flange 14, and a motor casing 20 15, is mounted on front wheels 16 and rear wheels 17, the latter wheels being provided with adjusting means 18 by which they may be moved relative to the cleaner body in order to lift it and adjust the nozzle 11 to and from the underlying portion of the floor covering which is to be cleaned. A rotary agitator 19 is preferably provided and rotatably mounted in the nozzle 11, extending transversely therein and driven by a belt, or other suitable means, from the shaft of 30 the vertical axis motor, which it will be understood is mounted in the motor casing portion 15. It will also be understood that a fan is located in the fan casing portion 12 and driven by the same motor. The bottom of the cleaner body is 35 preferably formed with an opening through which access may be had to the motor shaft, pulley and fan, and for removing the belt, such opening being normally closed by a removable cover plate 20, normally held in place by a latch 40 means 21. A rigid handle, provided with a bail 22, is provided for pushing the cleaner about over the floor covering, the bail 22 being pivoted to the body of the cleaner at 23 and provided with a suitable handle-position-controlling 45 means here shown as a sector 24, rigid with the handle bail 22 and cooperating with a latch means on the body of the cleaner, the arrangement and construction being such as to allow a limited range of free pivotal movement of the handle 50 from one intermediate position to another but to hold the handle releasably in the vertical, or storage, position shown in Figure 1, as well as in a horizontal position. All of the parts so far described are of well known construction and are

1

not described or shown in detail since they represent a typical embodiment of cleaner construction and their details constitute no essential part of the present invention. Such parts may vary 5 greatly as to detail structure, relative size, and location, and the present invention, which relates to the means of attaching the dust bag to a suction cleaner, may be embodied in any suction cleaner having a tubular outlet through which a 10 current of air is blown or sucked, and to which the dust filter is attached.

In the present embodiment a tubular fitting 25 is attached to the outlet flange 14, having a flange 26 corresponding in shape to that of the flange 14 15 with slotted ears 27 at its sides, so that it may be slid downwardly into registry with the flange 14 and secured by nuts 28 or similar means. The flange 26 is preferably grooved to receive a gasket 29, which is preferably formed of sponge rubber 20 faced with felt. The fitting 25 has an integral tubular extension 30, of uniform cross section and preferably oval, which extends upwardly at an angle substantially corresponding with that of the position of the handle during normal use of 25 the cleaner.

As shown in the drawings, a bag 31 is provided which is formed of air porous paper, or similar material, folded in pleats and open at its upper 30 end, the lower end being formed with a mouth which is relatively small by sewing the folds in overlapped relation, which structure is shown in greater detail in U. S. Patent 1,859,961, Ballou, issued May 24, 1932.

The mouth of the bag 31 is reinforced internally, by a short tube 32 of relatively stiff material, such as fiber or heavy paper or similar material, such tube being of uniform diameter throughout. A "valve" 33 may also be provided, if desired, in the form of a longer collapsible tube of 40 relatively flexible paper, cloth, or similar material, such valve tube being located between the bag mouth and the tube 32 and secured in place by stitching 34 extending through all three of the parts adjacent the mouth of the bag.

45 In order to secure the bag mouth to the tubular extension 30, a ring 35 is slidably mounted on the extension 30, such ring having a portion thereof slotted at 36 to form a plurality of spring fingers 37, one or more rivets 38 preferably being located 50 within one or more of the slots 36 to secure the ring 35 permanently to the extension 30 and limit the outward movement of the ring.

A gasket 35a is preferably provided on the extension 30, against which the base of the ring 35 55 seats, in order to prevent leakage, such gasket being preferably formed of sponge rubber faced with felt, or other suitable material. The ring 35 may be of rigid material having a tube of 60 spring material attached thereto, as shown, or may be formed as an entirety of spring material. In any case, the fingers 37 carried thereby are 65 resilient and are normally bent slightly inwardly, as shown in Fig. 2, the free ends of such fingers having short outwardly bent hook portions 39 adapted to engage back of the end of the tube 32, when the fingers 37 are forced outwardly, and it will be apparent that such fingers are forced 70 outwardly as the ring 35 is slid from the position shown in Fig. 2 to that shown in Fig. 3, being cammed outwardly by engagement with the end of the tubular extension 30.

The ring 35 is provided with a short radially extending lug 40 for engagement by a suitable latch means by which it may be detachably secured in the bag-retaining position shown in Fig. 75

3. As shown, the latch means comprises a member 41 of sheet metal having ears 42 bent over at each side thereof and pivoted at 43 to a lug 44 on the tubular fitting 25, and having short ears 45 bent out from the central portion thereof to which a retainer 46 formed of sheet metal is pivoted at 47. The retainer 46 is formed with a bent finger 48 at its end, and a coil spring 49 surrounds the pivot 47 and normally holds the end of the finger 48 in contact with the lug 44. The lug 44 is provided with notches 50 and 51 in which the finger 48 is engaged when the latch member 41 is in ring-securing and ring-releasing positions, respectively, and an arcuate surface 52 is provided between the notches 50 and 51 which is curved to approach the pivot point as it nears the notch 51, so that the pressure of the coil spring 49 will resist any tendency for the latch to fall back toward latching position after it has once been moved away from such position, even though the finger 48 is not engaged in notch 51. 10 15 20

The manner of using, the structure will be readily apparent. With the ring member 35 in the position shown in Fig. 2, the open mouth of the bag 31 is readily engaged over the hooked 25 ends 39 of the spring fingers and slid down until the lip of the bag mouth engages the abutment on the ring 35, as shown. As the length of the reinforcing tube 32 corresponds to the distance between such abutment and the hooked ends 39, 30 such hooked ends will be engaged with the inner end of the tube 32, when the ring 35 and the bag are slid together to the position shown in Fig. 3, the spring fingers being cammed outwardly by their engagement with the end of the tubular extension 30 and, when the latch 41 has been moved to the position shown in Fig. 3, the end 48 of the retainer 46 will be snapped into notch 50, and the bag will be securely locked in place. To release the bag it is only necessary to squeeze 40 together the latch member 41 and the latch retainer 46 to withdraw finger 48 from the slot 50, after which the bag 31 may be pulled off, the ring 35 moving with it until spring fingers 37 are free to spring inwardly to withdraw the hooked ends 45 39 from their engagement with the end of the tube 32.

In the modification shown in Figs. 8 and 9, spring fingers are shown which are compressed against the tube 32, instead of having latching 50 engagement with an abutment thereon. In this modified embodiment, the ring 35 has secured thereto a ring 59 of spring material which is slotted at 53, as in the first embodiment, to form fingers 54 each of which is bent back upon itself 55 and provided with a terminal tongue 55 engaged in a notch 56 near the base of the finger. The fingers 54 are thus wedge-shaped, thickening toward a loop at the inner end of each finger, and a filler ring 57 is preferably provided inside of the 60 ring 59 reaching substantially to the tongues 55. The upper end of the tubular extension 30a is beveled on its outer surface, as shown at 58, to provide for gradual compression of the spring fingers as the ring 35 is slid from the position 65 shown in Fig. 8 to that shown in Fig. 9. It will be apparent that, in general, the operation of this embodiment will be the same as that of the embodiment shown in Figs. 1 to 7, except that the bag will be frictionally held by the expansion of 70 the spring fingers outwardly against the reinforcing tube 32, rather than being positively latched in place by the hooked ends on the spring fingers engaging an abutment on the reinforcing tube.

While two embodiments of the invention have 75

been shown and described, it will be understood that various changes may be made in the details of construction and arrangement of parts without departing from the spirit of the invention, which is defined in the following claims:

5 I claim:

1. In a suction cleaner, the combination with a body having a discharge outlet terminating in a tubular extension, a sleeve mounted to slide lengthwise on said extension and having a radially expandable portion, and a dust bag having a neck portion adapted to be fitted over said sleeve in its extended position and then to be shifted bodily therewith onto said tubular extension whereby said expandable portion of said sleeve is expanded to engage said neck portion interiorly to hold said bag on said sleeve.

10 2. In a suction cleaner, the combination with a body having a discharge outlet terminating in a tubular extension, a sleeve mounted to slide lengthwise on said extension and having a radially expandable portion adjacent its outer end and adapted to assume a contracted position when extended beyond the end of said tubular extension, and a dust bag having a neck portion adapted to be fitted over said slideable sleeve in its extended position and then to be shifted bodily therewith onto said tubular extension whereby the normally contracted portion of said sleeve is expanded, and means mounted interiorly of the neck portion of said bag and adapted to be engaged by the expanded portion of said sleeve to hold said bag thereon.

15 3. In a suction cleaner, the combination with a body having a discharge outlet terminating in a tubular extension, a sleeve mounted to slide lengthwise on said tubular extension and having a radially expandable outer end portion adapted to assume a contracted position when the same is extended beyond the end of said tubular extension, and a dust bag having a neck portion adapted to be fitted snugly onto said sleeve in its extended position and to slide therewith onto said tubular extension and to be securely fastened thereto by the expansion of the outer end portion of said sleeve.

20 4. In a suction cleaner, the combination with a body having a discharge outlet terminating in a tubular extension, a sleeve mounted to slide lengthwise on said tubular extension and having a radially expandable and contractible outer end portion adapted to assume a contracted position when extended beyond the outer end of said tubular extension, a dust bag having a neck portion adapted to be fitted onto said sleeve in its extended position and to be shifted bodily therewith onto said tubular extension, and a collar surrounding the inner surface of said neck portion

25 having its innermost edge positioned to provide a shoulder to be engaged by the expandable end portion of said sleeve.

5 5. In a suction cleaner, the combination with a body having a discharge outlet terminating in a tubular extension, a sleeve mounted to slide lengthwise on said tubular extension and having at its outer end a plurality of radially expandable fingers normally assuming a contracted position when extended beyond the end of said tubular extension, and a dust bag having a neck portion adapted to fit snugly over said sleeve and to slide bodily therewith onto said tubular extension whereupon said fingers are expanded radially to engage said neck portion and hold said bag against displacement on said sleeve, and means for locking said sleeve against sliding movement on said tubular extension.

10 6. In a suction cleaner, the combination with a body having a discharge outlet terminating in a tubular extension with a shoulder at its lower end, a sleeve slidably mounted on said tubular extension and having a plurality of spring fingers forming its outer end portion, said spring fingers being radially contractible and expandable in the sliding movement of said sleeve on said tubular extension, a dust bag having a reinforced neck portion adapted to fit snugly onto said sleeve in its extended position then to slide bodily therewith onto said tubular extension flush with said shoulder thereof, whereupon said spring fingers are expanded radially to engage said neck portion to hold said bag on said sleeve, and latching means for holding said sleeve against sliding movement on said tubular extension.

15 7. In a suction cleaner, the combination with a body having a discharge outlet terminating in a tubular extension having a shoulder at its base, a sleeve mounted to slide lengthwise on said tubular extension and having its outer end portion slotted lengthwise to form a plurality of resilient fingers having their ends bent radially outward, said fingers being normally contracted when extended beyond the end of said tubular extension and adapted to be expanded radially in contact with said tubular extension, a dust bag having a neck portion adapted to fit said sleeve and have an internal reinforcing collar providing a shoulder at its innermost end, said neck portion being adapted to be inserted onto said sleeve in its extended position thence to slide therewith onto said tubular extension into flush contact with the shoulder at the base thereof, and a latching member mounted on said tubular extension adjacent said shoulder and adapted to have latching engagement with said sleeve when in flush contact with said shoulder.

20 35 40 45 50 55 HAROLD H. BOYER.
